(57) **CLAIM**

The ornamental design for an electric toilet lift, as shown and described.

DESCRIPTION

FIG. 1 is a perspective view of an electric toilet lift showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is the same as perspective view in FIG. 1 except in the lifted position.

1 Claim, 8 Drawing Sheets
